UNITED STATES PATENT OFFICE

119,558

DESIGN FOR A WATCHCASE

Fred Rieger, Jamaica, N. Y., assignor to William
M. Welling, New York, N. Y.

Application January 31, 1940, Serial No. 89,896

Term of patent 3½ years

To all whom it may concern:

Be it known that I, Fred Rieger, a citizen of the United States, residing at Jamaica, in the county of Queens and State of New York, have invented a new, original, and ornamental Design for a Watch Case, of which the following is a specification, reference being had to the accompanying drawing, forming part thereof.

Figure 1 is a front elevational view of a watch case, showing my new design.

Figure 2 is an end elevational view, Figure 3 is a rear elevational view of the disclosure in Figure 1, and

Figure 4 is a top plan view of the watch case.

I claim:

The ornamental design for a watch case, as shown.

FRED RIEGER.
